UNITED STATES PATENT OFFICE.

BYERS W. KADEL, OF BALTIMORE, MARYLAND.

CAR-DOOR MECHANISM.

Application filed January 30, 1925. Serial No. 5,796.

This invention relates to railway cars and particularly to mechanism for supporting the doors thereof. A principal object of the invention is to provide improved means for supporting a car door in a preliminary position of closure and also in a more completely closed position. A further object is to provide door supporting means involving a hook shaped member rigidly secured to the door for cooperation with a pivoted latching member attached to the car body. Other more specific objects and features of the invention, all contributing to the general object of providing improved means for supporting car doors, will hereinafter appear and be pointed out in the claims.

In the accompanying drawings showing a preferred form of the invention,—

Figure 1 is a fragmentary side elevational view of the hopper portion of a car of the well known twin hopper type, mechanism embodying the invention being shown in connection therewith.

Figure 2 is a fragmentary transverse sectional view on the line 2—2 of Fig. 1.

Figure 3 is a view similar to Fig. 1 but illustrating a modified form of the invention.

Referring to the drawings, the side of the car, which in the present instance is formed by the hopper end sheet, is indicated by the numeral 1. The margin 2 of this sheet or plate 1 is outwardly offset along the edge of the hopper discharge opening to form a seat 3 against which the door 4 is adapted to close. The plane of the plate portion of the door 4 is spaced or removed slightly from the outermost edge 2 of the side sheet 1 so that the portion of the latter which extends outwardly beyond the shoulder 3 constitutes a sealing flange for cooperating with a sealing and stiffening flange 5 which defines the outer edge of the door. This sealing flange 5 at the free edge of the door stands parallel with and just inside of the flanged edge of the side sheet 1 of the car when the door is closed. The door 4 is hinged along its upper edge and is adapted to swing open under the influence of gravity. The hinge connection for the door is not illustrated in the drawings as it is well known in the art and may be effected in any suitable manner.

Mounted upon the outer face of the door 4 is a door stiffening member 6 which also may constitute a door spreader or connector in cases where the door is constructed as a

plurality of plates for closing distinct hopper discharge openings on opposite sides of the car. In the present embodiment the spreader 6 is in the form of a modified channel section whose web abuts against and is secured to the outer face of the door plate and whose main flanges extend outwardly therefrom, said main flanges being provided along their outermost ends with comparatively narrow return flanges. It is to be understood, of course, that while the preferred form of door stiffener 6 is advantageous for association with the parts of the mechanism to be described, the particular form of said stiffening member is not essential.

Rigidly mounted upon the door 4 and preferably attached to the stiffening member 6 is a door supporting member 7. This member is preferably held rigidly in position by means of rivets 8 which pass through the web of the stiffening member 6 and through the door plate. A portion of the member 7 is offset outwardly beyond the outer edge of the door so as to clear the sealing flange 5 and the flanged edge 2 of the car side, and said member 7 is bent at right angles to the plane of the door so as to provide a portion 9 which overlies the side of the car or hopper end sheet 1 when the door is in closed position.

The arm 9 of the member 7 carried by the door, as shown in Figs. 1 and 2, is formed as an upwardly facing hook having a latch seat or ledge 10 preferably extending in a plane approximately parallel to that of the door when the latter is closed. The end of the hook is sloped or beveled as at 11 just in advance of the ledge 10 so as to constitute an approach plane for lifting the pivoted latch 12 when the door is swung toward closed position.

Pivotedly mounted upon the car on the outer face of the hopper end sheet 1 is a latching member 12 which is adapted to cooperate with the hook 9 to support the door either in fully closed position or in a preliminary position of approximate closure. For this purpose the latch 12 is preferably formed at its free end with a main shoulder 13 capable of engaging the ledge 10 of the hook to hold the door in closed position, and also is provided between its ends with an auxiliary shoulder 14 capable of cooperating with the ledge 10 of the hook to sup-

port the door in partly closed position. A locking cam 15 is pivotally mounted upon the car just above the latch 12. When this cam is rotated to latch releasing position 5 the latch 12 may be disengaged from the ledge 10 of the member 7; and when the said latch is in door supporting engagement with the said ledge the cam may be driven down so as to wedge against the latch 12 10 and lock the latter in door supporting engagement with the hook member 7. Upon the door 4 swinging open the latch 12 will automatically swing under the influence of gravity to a substantially perpendicular position; and when the door is pushed towards closed position, as for example by pressure from the foot of the attendant, the approach portion 11 of the hook member 7 will contact the freely swinging latch 15 20 and will rotate the latter upwardly to a position enabling its preliminary latching shoulder 14 to drop behind the ledge 10 and thereby support the door in partly closed position. Force may then be applied to the door 4, either by the foot or by suitable prying means, to move said door to 25 fully closed position permitting the main shoulder 13 of the latch to drop into overlapping engagement with the ledge 10 of the hook. When the ledges 10 and 13 of the hook and latch, respectively, are in door supporting relation, the cam 15 may be driven into locking engagement with the upper surface of the latch 12, thus locking 30 the door shut. Rivets or other suitable means may be employed for pivotally mounting the latch 12 and cam 15 upon the side of the car and a reinforcing member 16 may advantageously extend from the pivot point of the latch 12 to the pivot point 35 of the cam 15, thereby preventing the pivotal points of these parts from wedging apart when the cam is forced into locking engagement with the latch.

40 In the embodiment of the invention illustrated in Fig. 3 the pivoted latching member 17 mounted upon the side of the car has but a single shoulder 18 for cooperating with the fixed hook member 7 carried by 45 the car door. But in order to support the door in partly closed position as well as in a position of final closure, the hook member 7 is provided with a plurality of spaced wedges 19 with each of which the shoulder 50 55 18 of the latch is adapted to engage. By these means the door 4 may be supported in different positions of closure, as will be readily understood.

As the remaining details of construction of the modified form of the invention shown in Fig. 3 are substantially the same as those heretofore described, they have been identified by corresponding reference numerals.

60 While preferred forms of the invention have been illustrated and described it is to

be understood that other embodiments thereof are contemplated within the scope of the appended claims.

I claim:

1. A railway car having a door adapted to swing open under the influence of gravity, and means for supporting the door against an opening movement, said means involving a hook member rigidly secured to the door, a latch member pivoted upon the car body and adapted to engage said hook member, and means operable independently of the latch for releasably maintaining the latch member in door supporting engagement with said hook member. 70 75 80

2. A railway car having a door adapted to swing to open position under the influence of gravity, and means for supporting said door against an opening movement, said means involving a hook member rigidly secured to the door, a latch member movably mounted upon the car body and adapted to engage said hook member to thereby support said door, one of said members being provided with a plurality of faces for engaging the other of said members, whereby the door may be supported in different positions of closure, and means for releasably maintaining said latch member in engagement with said hook member. 85 90 95

3. A railway car having a door adapted to swing open under the influence of gravity, said door having an edge substantially parallel with an adjacent portion of the side of the car, a hook member rigidly secured to the door and adapted to overlap the side of the car when the door is closed, and a latch member pivoted upon the car side and adapted to engage said hook member to support said door against opening movement, one of said members having a plurality of faces either of which is adapted to engage the other of said members to prevent an opening movement of said door. 100 105 110

4. A railway car having a door adapted to swing open under the influence of gravity, and means for supporting said door against an opening movement, said means involving a hook member carried by said door, and a latch member movably mounted upon the car body, said latch member being provided with a plurality of shoulders each of which is adapted to engage a shoulder upon said hook member to support said door against opening movement. 115 120 125

5. A railway car having a door adapted to swing open under the influence of gravity, and means for supporting the door against an opening movement, said means involving an upwardly facing hook rigidly secured to said door and adapted to overlap the side of the car body when the door is closed, a latch member pivotally mounted upon the car body above said hook member and adapted to engage the latter to support said door 130

against an opening movement, and means for maintaining said latching member in door supporting engagement with said hook member.

- 6 6. A railway car having a door adapted to swing open under the influence of gravity, and means for supporting the door, said means involving a hook member rigidly mounted upon said door, a latch member pivoted to the car side and adapted to engage said hook member to support the door against opening movement, and means for maintaining said latch member in door supporting engagement with said hook member,
- 10 15. said hook member being adapted to pass beneath the pivot point of said latch member during a closing movement of said door.

7. A railway car having a hinged door and means for supporting said door against an opening movement, said means involving a pivoted latch member, a hook member having angularly extending portions one of which overlaps said door and the other of which is adapted to overlap the side of the car, said last named portion being provided with a shoulder for engaging said latch member, and means for maintaining said latch member in door supporting engagement with said shoulder, said latch member having its pivotal point between said shoulder and the door when the latter is closed.

In testimony whereof I affix my signature.
